FOOTBALL KICKING TEE

Benjamin J. Agajanian, Long Beach, Calif.

Application November 13, 1953, Serial No. 27,584

Term of patent 3½ years

(Cl. D34—5)

FIG. 1.

FIG. 2.

FIG. 3.

FIG. 4.

To all whom it may concern:

Be it known that I, Benjamin J. Agajanian, have invented a new, original, and ornamental Design for a Football Kicking Tee, of which the following is a specification, reference being had to the accompanying drawing, forming a part hereof.

The flat square area in Figure 1 is stippled to indicate contrasting color to the remainder of the article.

I claim:

The ornamental design for a football kicking tee substantially as shown and described.
